FIG. 1.

FIG. 2.

FIG. 4.

FIG. 5.

FIG. 1 is an isometric view of a hand stamp embodying the new design of this invention;

FIG. 2 is an exploded elevational view showing the hand stamp of FIG. 1 as it appears with the cap removed therefrom;

FIG. 3 is a top plan view of the hand stamp as shown in FIG. 1;

FIG. 4 is a bottom plan view of the hand stamp as it appears without the cap; and

FIG. 5 is a bottom plan view of FIG. 1.

The essential features of the design reside in the portions shown in solid lines, a conventional stamp being shown in broken lines in FIGS. 2 and 4.

We claim:

The ornamental design for a hand stamp, substantially as shown and described.
